UNITED STATES PATENT OFFICE.

RUDOLF SALMEN, OF CHICAGO, ILLINOIS.

FLYING-MACHINE.

1,025,999.

Specification of Letters Patent. Patented May 14, 1912.

Application filed December 23, 1909. Serial No. 534,607.

To all whom it may concern:

Be it known that I, RUDOLF SALMEN, a citizen of the United States of America, and resident of Chicago, Cook county, Illinois, 5 have invented a certain new and useful Improvement in Flying-Machines, of which the following is a specification.

My invention relates to flying machines of the aeroplane type.

10 Objects of my invention are to provide an improved arrangement of the supporting planes; to provide an improved arrangement of the rudder for steering the machine to the right or the left; to provide an improved 15 arrangement of the planes for causing the machine to rise or fall from one level to another; to provide an improved framework for the machine; and to provide certain novel combinations tending to increase 20 the general efficiency.

To the foregoing and other useful ends, my invention consists in matters hereinafter set forth and claimed.

In the accompanying drawings, Figure 1 25 is a side elevation of a flying machine embodying the principles of my invention. Fig. 2 is a plan of the said machine.

As thus illustrated, my invention comprises a rectangular and longitudinally disposed skeleton frame A composed of the upper longitudinal members a—a, and the lower longitudinal members a'—a', which 30 are connected by the crossed members a² and a³. The members a are connected with the members a' by means of vertical members a⁴, a⁵, a⁶ and a⁷. The members a⁴ and a⁵ extend below the members a', and at their lower ends are connected by the short 35 longitudinal members a⁸. The axle for the front supporting wheels B is connected with the front of the frame A by means of the braces b, which latter are also joined with the lower ends of the members a'. This 40 axle is also connected by the braces b' with the top of the rear portion of said frame. The long braces b² extend from the extreme front of the frame members a to the axle of the rear wheels C, which axle is mounted 45 on the lower ends of the brackets c secured to the members a⁸. In this way a strong but very light frame is provided. Preferably, the two axles are connected by members c, as shown. The machine is of the biplane type, and has upper and lower main 50 supporting planes D and E, which are arranged transversely of the rear end of the

frame. The plane E is suitably secured upon the members a⁸ and the plane D is mounted above on the members a, each plane being made of any suitable material and constructed in any suitable manner. One or more propellers F are placed at the rear of these planes, and operated by suitable motive power.

A relatively small and fixed supporting 65 plane G is disposed upon the forward end of the frame A. A flat deck or plane H fills the space between the members a, a', and the planes D and G. The vertical plane or rudder I is disposed below the plane G, at 70 the center thereof, and is controlled in any suitable manner to steer the machine to the right or the left. The horizontal planes J are disposed below the deck or plane H, at 75 opposite sides of the frame A, and are mounted upon the ends of the shaft j, which latter is supported in suitable bearings on the frame members a'. These planes J are controlled in any suitable manner to deflect the machine from one level to another. Thus 80 it will be seen that I provide a fixed plane in front of the main planes, and that the rudder I is below the fixed plane. The horizontal rudders or dipping planes J are, however, in rear of the vertical rudder I 85 and the forward fixed plane G. A rider's seat K may be provided between the main planes.

What I claim as my invention is:

1. In a flying machine, a longitudinal 90 frame, a pair of main planes at the rear of said frame, disposed one over the other, the upper one being at the top of the frame, a relatively small plane at the forward end of said frame, which small plane bears a fixed 95 relation to said main planes, and a flat deck between said front and rear planes, the said small plane and deck being at the top of the frame.

2. In a flying machine, a longitudinal 100 frame, fixed planes at the front and rear ends thereof, the front plane being much smaller than the rear plane, and a dipping plane or horizontal rudder intermediate the front and rear fixed planes, disposed at a 105 substantially lower level, said rudder consisting of two small planes spaced apart and connected to work in unison, as set forth.

3. In a flying machine, a frame composed of upper and lower longitudinal members, 110 connecting members therefor, a vehicle, braces running from the front ends of the

lower members to the front of said vehicle, 5
braces running from the forward end of the
upper members to the rear of said vehicle,
braces running from the rear ends of the up-
per members to the front of said vehicle,
short lower longitudinal members, and
planes on the frame.

4. In a flying machine, a rear main trans-
verse plane, a front transverse plane, said
10 planes being disposed horizontally and fixed
relatively to each other, a vertical rudder
immediately below said front plane, at the
head of the machine, movable about a verti-
cal axis to steer the machine to right or left,
15 said front plane being smaller than the said
main plane, and a horizontal rudder dis-
posed between said planes, movable about a
horizontal axis to raise and lower the ma-
chine, said horizontal rudder being lower
20 than the vertical rudder.

5. In a flying machine, a rear main trans-
verse plane, a front transverse plane, said
planes being disposed horizontally and fixed
relatively to each other, a vertical rudder
25 immediately below said front plane, at the
head of the machine, movable about a verti-
cal axis to steer the machine to right or left,
said front plane being smaller than the said
main plane, and a horizontal rudder dis-
30 posed below the level of said planes, movable
about a horizontal axis to raise and lower
the machine, said horizontal rudder being
lower than the vertical rudder.

6. In a flying machine, a rear main trans-
verse plane, a front transverse plane, said
35 planes being fixed relatively to each other,
a vertical rudder immediately below said
front plane, at the head of the machine,
movable about a vertical axis to steer the
40 machine to right or left, said front plane
being smaller than the said main plane, and
a horizontal rudder disposed between said
planes, movable about a horizontal axis to

raise and lower the machine, said horizon-
tal rudder consisting of two small planes 45
spaced apart and mounted at opposite sides
of the machine, the length over all of said
horizontal rudder being substantially the
same as the front plane, whereby the ends
of said front plane overhang the paths of 50
travel of the two small planes, as set forth.

7. In a flying machine, a rear main trans-
verse plane, a front transverse plane, said
planes being fixed relatively to each other, a
vertical rudder immediately below said 55
front plane, at the head of the machine, said
front plane being smaller than the said
main plane, a horizontal rudder disposed be-
tween said planes, another plane below the
main plane, and a flat deck between the 60
main plane and said front plane, the said
horizontal rudder consisting of two small
planes disposed at opposite sides of the ma-
chine at points below the level of said main
plane and front plane. 65

8. In a flying machine, a rear main trans-
verse plane, a front transverse plane, said
planes being fixed relatively to each other,
a vertical rudder immediately below said
front plane, at the head of the machine, 70
movable about a vertical axis to steer the
machine to right or left, said front plane
being smaller than the said main plane, a
horizontal rudder disposed between said
planes, movable about a horizontal axis to 75
raise and lower the machine, and a rear
propeller the axis of which is intersected,
or substantially so, by the axis of said rudders,
said horizontal rudder being lower
than the vertical rudder. 80

Signed by me at Chicago, Illinois, this
16th day of December, 1909.

RUDOLF SALMEN.
